UNITED STATES PATENT OFFICE.

DAVID D. GORDON, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLUG.

1,320,135.

Specification of Letters Patent. Patented Oct. 28, 1919.

Application filed March 6, 1916. Serial No. 82,338.

To all whom it may concern:

Be it known that I, DAVID D. GORDON, a citizen of the United States, residing at Chicago, in the county of Cook and State 5 of Illinois, have invented a certain new and useful Improvement in Plugs, of which the following is a full, clear, concise, and exact description, reference being had to the accompanying drawings, forming a part of 10 this specification.

My invention relates to plugs for making electrical connections, and more particularly to that style of plugs called separable attachment plugs. My invention has for its 15 object the provision of a new and improved style of separable attachment plug, in the preferred form of which the separable member to which the cord is connected carries one of the contact elements which is adapted directly to establish electrical connection 20 with one of the socket contact elements without the interposition of an intermediate conducting portion on the coöperating portion of the plug.

I will explain my invention more in detail by referring to the accompanying drawings illustrating one embodiment thereof, in which

Figure 1 is a longitudinal sectional view 30 of a plug constructed in accordance with my invention as mounted in a socket;

Fig. 2 is a side view of the two plug members in their separated condition;

Fig. 3 is a sectional view of the plug and 35 the contact portion of the socket on line *a* of Fig. 1;

Fig. 4 is a view looking at the separable part of the attachment plug in the direction of the arrow *b* in Fig. 2;

Fig. 5 is a sectional view of a modified 40 form of socket;

Fig. 6 is a top view thereof;

Fig. 7 is a longitudinal view of a plug 45 adapted to coöperate with the socket of Fig. 5;

Fig. 8 is a view looking toward the contact making portions of the separable part of the plug shown in Fig. 7, and

Fig. 9 is a side view of the plug shown 50 in Fig. 7.

Referring more particularly to Fig. 1, I show a socket 1 having the central contact element 2 and the outer screw threaded contact element 3. My improved plug 4 is 55 adapted to coöperate with this socket, this

plug being more clearly shown in Figs. 2, 3 and 4. This plug consists of two separable body members 5 and 6. The member 5 is made of insulating material and does not carry the customary screw shell on its periphery, but has its insulating body portion formed with a screw threaded periphery as clearly apparent from the figures. This body member has a central contact element 7 which, when this body member is 60

in position, coöperates with the central contact element 2 of the socket. The contact member 7 is extended upwardly as shown at 8 and may terminate in a spring contact finger 9, which spring contact member 70 projects into the open space 10 that is formed within this body member 5. The said body member 5 also has a further open space 10^a, which however takes the form of a groove, at which point a portion of the 75 periphery, as shown more clearly in Figs. 2 and 3, is cut away. This groove extends as a slot 11 preferably where it passes through the portion 12 which is supposed to be

grasped by the fingers when inserting this 80 body member 5 into the socket if it should be desired to insert this body member independently of the body member 6. The coöperating body member 6 has a spring contact finger 13 which is fixedly secured to 85 said body member and which is adapted to project into the open space 10 and form electrical contact with the spring contact finger 9 when these two coöperating members are in their unseparated condition as 90 shown in Fig. 1. This body member 6 further has a second spring contact finger 14. The contact fingers 13 and 14 are then adapted respectively to be electrically connected with the entering cord members 15 95 and 16. The spring finger 14 is adapted to enter through the slot 11 and then projects into the open space 10^a where, by reason of its spring action, if the plug is not in the socket this spring finger 14 normally projects outwardly beyond the periphery slightly of said body member 5. Thus it will be seen that this spring contact finger 14 itself normally engages the inner screw threaded contact 3 of the socket when the 100 plug is in position as shown in Fig. 1.

Now assume that it is desired to disconnect the circuit, then the body member 6 (Fig. 1) is pulled to the right, whereupon the spring finger 14 is pulled away from its 110

association with the contact 3 and the spring finger 13 is also drawn away from engagement with the spring finger 9. Thus the body member 5 has provision for containing 5 only one side of the circuit, the other side of the circuit being accommodated for and its continuity provided for solely by the means associated with the body member 6. It will be seen that the two elements of the 10 plug are normally yieldingly locked together as they should be, the particular means herein shown to serve this purpose being the offset portions of the spring fingers 9 and 13, as shown for instance at 17.

15 From what has been described it will be readily seen that the plug provides contact facilities for continuing the circuit through the two contact portions of the socket, the body member 6 having provision for conducting portions of both sides of the circuit, and the body member 5 having provision for the conducting portion of but one side of the circuit. The great simplicity of thus constructing a plug will be readily apparent 20 25 as it is seen that the plug comprises very few parts and yet serves the purposes normally served by separable attachment plugs.

Referring more particularly to Figs. 7 and 9, I show a modified form of plug having 30 a central contact 22 and an outer screw threaded contact 23 which extends only along a portion of the periphery of this plug, as shown more clearly in Fig. 9. This provides a cheap plug construction in that 35 the central contact 22 and the screw threaded portion 23 can both be provided with extending spring contact fingers 24 and 25 to which the spring fingers 26 and 27 of the separable portion 28 of the plug can find 40 ready attachment.

In Fig. 5 I show an improved style of socket construction in which the socket 18 has the customary central contact 19 and the customary screw threaded contact portion 45 20. The socket 18, is designed for instance for wall purposes. In sockets of this nature the plug is frequently removed, thus leaving the inner portion of the socket exposed and it very frequently happens that 50 children insert their fingers into the socket and thus receive a shock by touching both the terminals 19 and 20. My improved socket avoids this difficulty by providing a conducting finger 29 insulatingly mounted in 55 the socket. Finger 29 shields the central contact 19. Thus if the finger is inserted into the socket no shock would be obtained as the finger 29 normally does not engage the contact 19. The danger of shock is thus 60 entirely avoided, but it will of course be readily apparent that when a plug is inserted and screwed into the socket, that the spring finger 29 is then bent to engage the center contact 19 and thus establish continuity of the circuit. When the plug is 65

withdrawn, however, the spring finger 29 again assumes the position shown in Fig. 5 and safeguards against shock.

From what has thus been described it is thought the nature of my invention will be 70 clear to those skilled in the art. Having however thus described specific means for carrying out my invention, what I claim as new and desire to secure by Letters Patent is:

75 1. A connecting device of the character described comprising two separable body members, one of said body members having means adapted to hold it in a socket having a screw threaded contact terminal, said other body member having two contact terminals, the outer one of which is adapted to directly engage the screw threaded contact terminal of said socket, and means for yieldingly locking said body members together. 80 85

2. A connecting device of the character described comprising two separable body members, one of said body members having means adapted to hold it in a socket having a screw threaded contact terminal, said other body member having two contact terminals, the outer one of which is adapted to directly engage the screw threaded contact terminal of said socket, and means for yieldingly locking said body members together, said first aforesaid body member having a conducting portion adapted to engage the other terminal of said socket, and separable conducting means provided on 90 95 said body members adapted for electrical association with said last aforesaid conducting portion. 100

105 3. A connecting device of the character described comprising two separable body members, one of said body members having means adapted to hold it in a socket having a screw threaded contact terminal, said other body member having two contact terminals, the outer one of which is adapted to directly engage the screw threaded contact terminal of said socket, and means for yieldingly locking said body members together, said first aforesaid body member having a conducting portion adapted to engage the other terminal of said socket, and separable conducting means provided on 110 115 said body members adapted for electrical association with said last aforesaid conducting portion, said first aforesaid body member having a cut away portion to accommodate the contact terminal of said second body member which is adapted directly to engage a socket terminal. 120

125 4. A connecting device of the character described comprising two separable body members, one of said body members having means adapted to hold it in a socket having a screw threaded contact terminal, said other body member having two spring con- 130

tact terminals, the outer one of which is adapted to directly engage the screw threaded contact terminal of said socket, and means for yieldingly locking said body members together.

5. A connecting device of the character described comprising two separable body members, one of said body members having means adapted to hold it in a socket having a screw threaded contact terminal, said other body member having two contact terminals, the outer one of which is adapted to directly engage the screw threaded contact terminal of said socket, means for 10 yieldingly locking said body members together, and means on said second body member for receiving the terminals of a connecting cord.

6. A connecting device of the character 15 described comprising two separable body members, one of said body members having means adapted to hold it in a socket having a screw threaded contact terminal, said other body member having two spring con-

taet terminals, the outer one of which is 25 adapted to directly engage the screw threaded contact terminal of said socket, means for yieldingly locking said body members together, and means on said second body member for receiving the terminals of a connecting cord.

7. A connecting device of the character described comprising two separable body members, one of said body members having means adapted to hold it in a socket having 30 a screw threaded contact terminal, said other body member having two contact terminals, one of which is adapted to directly engage the screw threaded contact terminal of said socket.

In witness whereof, I hereunto subscribe my name this 21st day of February, A. D., 40 1916.

DAVID D. GORDON.
